(57) CLAIM

I claim the ornamental design for a jacket, as shown and described.

DESCRIPTION

FIG. 1 is a front elevational view a jacket showing my new design; and,

FIG. 2 is a rear elevational view thereof.

The dashed lines shown in the drawing views represent stitching lines.
